SLIDE FASTENER ACTUATOR

Herman Epstein, 1210 E. 9th St.,
Kansas City, Mo. 64106

Filed July 18, 1966, Ser. No. 3,105

Term of patent 14 years

(Cl. D2—415)

FIG. 1 is a front elevational view of a slide fastener actuator, showing my design.

FIG. 2 is a rear elevational view thereof.

FIG. 3 is a side elevational view thereof, and

FIG. 4 is a bottom view thereof.

A portion of the suspension member of the slide fastener actuator has been omitted from FIGS. 1-4 to indicate variable and indeterminate length.

I claim:

The ornamental design for a slide fastener actuator, as shown and described.
